VACUUM CLEANER

Axel Albert Forsberg, Stockholm, Sweden, assignee to Electrolux Corporation, Dover, Del., a corporation of Delaware

Application June 6, 1936, Serial No. 83,836
In Germany June 14, 1935

14 Claims. (Cl. 183—37)

The present invention relates to vacuum cleaners and particularly to means for indicating the amount of dirt collected within a vacuum cleaner.

As dirt collects within the dust bag of a vacuum cleaner, or within a dust collecting chamber one or more walls of which includes a dust separating member, the accumulated dust interferes with the flow of air. As the dust collects it tends to clog the pores of the dust separating member, thereby increasing the pressure drop through the member. Consequently, this pressure drop may be employed to indicate the amount of dirt which has accumulated. An increase in pressure drop also results in a decrease 10 in velocity of the air passing through the cleaner unit, and hence the decrease in velocity may be employed to indicate an increase in accumulation of dust.

In apparatus of this type heretofore known, 20 the indicator member has been arranged to give a reading determined by either the pressure drop or the velocity of the air flow at the particular instance when the indicator is observed. Consequently, the indicator gives no true indication 25 of the amount of dust accumulated if it is observed while the fan is stationary. An indicator dependent upon pressure drop will indicate a clean dust bag whenever the fan is stationary, inasmuch as there is no pressure drop under these 30 conditions, regardless of what the true amount of dust accumulated may be. Likewise, an indicator responsive to air velocity will show dirty whenever the motor is stopped, regardless of how much dirt is actually accumulated. Moreover, 35 both types of indicators give fluctuating reading during use of the vacuum cleaner, inasmuch as they are affected to some extent by the resistance to flow through the nozzle. If the nozzle opening is substantially sealed, as by being 40 pressed against rugs of a certain type, the air flow will be substantially prevented and consequently much the same condition will exist as does when the motor is stopped. Hence, it is 45 difficult for the operator to know whether the indicator at any particular instant is giving him a true reading.

One of the objects of this invention is to provide an indicator which records maximum values. 50 As will later appear, the maximum value of the pressure drop through the dust separating member bears a definite relationship to the amount of dust accumulated. In accordance with the present invention, the indicator records this maximum reading so that the operator may know at

all times, even when the motor has been stopped, the amount of dust in the cleaner.

Another object of the invention is to provide means for returning the indicator to a zero reading in response to a manual operation. Preferably, the indicator is returned to zero when the dust separating member is removed from the cleaner unit.

Another object of the invention, is to provide means in combination of the above for aiding in the removal of the dust separating member. Further objects of the invention will be apparent from the following description considered in connection with the accompanying drawings, and of which:

Fig. 1 is a side view, partially in cross-section, of one embodiment of the invention;

Fig. 2 is an enlarged view of a portion of the device shown in Fig. 1;

Fig. 3 is a cross-sectional view of a part of a 20 vacuum cleaner showing a second embodiment of the invention;

Fig. 4 is a cross-sectional view of the line 4—4 of Fig. 3;

Fig. 5 is a cross-sectional view of the portion of 25 a vacuum cleaner showing a third embodiment of the invention;

Fig. 6 is a cross-sectional view showing a fourth embodiment of the invention;

Fig. 7 is a cross-sectional view showing a fifth 30 embodiment of the invention;

Fig. 8 is a cross-sectional view of a sixth embodiment of the invention;

Fig. 9 is a cross-sectional view showing a seventh embodiment, and is taken on the line 35 9—9 of Fig. 11;

Fig. 10 is a cross-sectional view of the device shown in Fig. 9 and is taken on the line 10—10 of Fig. 11;

Fig. 11 is an end view of a portion of the device 40 shown in Figs. 9 and 10; and

Fig. 12 is a cross-sectional view of an eighth embodiment of the invention.

Referring more particularly to Figs. 1 and 2, reference character 10 designates a casing of a 45 vacuum cleaner unit. Mounted within casing 10 is an electric motor 11 arranged to drive a centrifugal fan 12 disposed within a fan housing 9 having an inlet 13. The fan exhausts through and around the motor and the air is discharged 50 to the atmosphere through an outlet opening 14.

The left end of casing 10, as viewed in Fig. 1, is provided with a ring 15 formed with an outer face 16 against which is adapted to be seated a dust bag ring 17. Ring 17 is formed with an 55

outwardly extending flange 18 carrying a packing member 19 of rubber or the like. Flange 18 and packing 19 is adapted to be clamped against the face 16 of ring 15 by means of a closure member 20, which may be secured to the casing 10 by means of spring clips 23 or the like. Closure member 20 is formed with an inlet opening 24 to which may be attached a hose 25 leading to a nozzle 26.

10 Secured to ring 17 is a dust separating member 27, in the form of a bag having a closed end. A perforated plate 28 is resiliently mounted on fan housing 9 by means of one or more springs 29 and the length of bag 27 with respect to the distance between ring 17 and plate 28 is so chosen that the plate prevents complete distension of the bag.

20 Slidably mounted in the upper part of casing 10 in the space 31 between the dust bag and the casing is a preferably tubular member 30 having a horizontal portion supported in brackets 33, 34 and 35. Member 30 also includes a portion 36 which extends radially of the casing and has an axial portion 37 adapted to contact the central part of plate 28, but is not secured to the plate.

25 Mounted on the upper part of casing 10 is a handle bracket 38 having an air tight compartment 39 within which is rotatably mounted an indicator member 40. Indicator 40 includes the semi-cylindrical portion, the outer surface of which has printed or otherwise impressed thereon a legend or the like for indicating its position. The outer surface of the indicator is visible 35 through an air tight window 43 formed in housing 38. An arm 44 extends from the center of indicating member 40 and engages within a slot formed in member 30, whereby longitudinal movement of the member 30 causes rotation of 40 the indicator.

30 Slidably mounted within ring 15 is a resetting rod 45 which telescopes within the end of tubular member 30. Member 30 is formed with a slot 46 and rod 45 is provided with a projection 47 which may slide within the slot 46. A coil spring 48 is arranged around rod 45 between bracket 35 and a collar 49 formed on the rod. The left hand end as viewed in Fig. 2 of rod 45 is preferably formed with an enlargement 50 adapted 50 to be received in a recess formed in the face 16 of ring 15 and to press against the dust bag ring.

55 The operation of the above described apparatus is as follows:

55 - Rotation of fan 12 by the motor 11 causes air to be drawn in through nozzle 26, hose 25, and inlet opening 24 into the interior of dust bag 27. If the nozzle is passed over a dusty surface, dust will be entrained with the air and carried into 60 the dust bag. The bag is made of a suitable material which is impervious with respect to dust, but permits the passage therethrough of air. Consequently, the dust accumulates within the dust bag, while the air passes through the 65 material thereof to the fan from whence it is discharged to the atmosphere through opening 14.

70 The material of the dust bag at all times offers some resistance to the flow of air there- 70 through and consequently there is a pressure drop through the bag which causes a lower pressure to exist in the space 31 than exists within the bag 27. Hence, there is a tendency for the bag to be distended to its fullest extent, 75 and therefore the closed end of the bag presses

against plate 28 and tends to compress the spring 29. With a clean bag the resistance to flow, and hence the pressure drop, is comparatively small and the springs 29 are designed to resist the tendency of the bag to distend. However, as dust accumulates within the bag it fills more or less the pores in the material of the bag through which the air passes, thereby increasing the resistance to flow. This in turn causes an increase in the pressure drop and the force exerted by the bag against the plate increases, and this moves the plate to the right as viewed in the figures, and compresses spring 29. The movement in this direction of plate 28 causes tubular member 30 to move in a similar direction, thus causing indicator member 40 to rotate in a counter clockwise direction. During this movement of tubular member 30, rod 45 remains stationary, the tubular member being able to slide with respect thereto by virtue of the fact that projection 47 may slide within slot 46. If the motor is now stopped the flow of air through the cleaner ceases and the pressure on opposite sides of the dust bag is equalized. Consequently, the springs 29 return the plate 28 to its original position. 25 However, member 30 does not follow the movement of plate 28 in this direction inasmuch as it is not attached to the plate, and there is no force acting on the rod tending to move it to the left. The openings in brackets 33, 34 and 35 fit 30 the member 30 with such tightness so that the friction prevents accidental displacement of the member 30 in either direction. Therefore, the indicator member 40 remains in the furthest position to which it was rotated by movement of member 30 to the right, and records a reading proportional to the maximum pressure drop through the dust bag.

40 If the motor is again started and more dust accumulates within the bag, the increase in pressure drop causes the plate 28 and the rod 30 to be moved further to the right and this new maximum reading is recorded by the indicator member 40.

45 Likewise, fluctuation in pressure drop occurring during the operation of the cleaner does not affect the indicator member. If the nozzle 26 is substantially sealed, the flow of air through the unit including the flow of air through the dust bag practically ceases, whereupon the pressure 50 drop through the bag amounts to practically nothing. This permits the springs 29 to move the plate 28 to the left but this movement is not communicated to the indicator member 40, which at all times records the maximum pressure drop 55 which has occurred through the bag since the machine was first started. When a sufficient amount of dust has been accumulated in the bag to require the cleaning thereof, this fact is made known to the operator by the position 60 of the indicator member 40. To clean the bag closure member 20 is removed by unfastening clip 23, whereupon the dust bag ring 15 may be grasped and the bag removed from the casing 10. As soon as the ring is moved away from 65 the end 50 of rod 45, spring 48 moves the rod to the left, as viewed in the figure, and projection 47 on the rod engages the left hand end of slot 46 in member 30, thus causing member 30 to be moved to the left. This rotates indicator member 40 in a clock-wise direction and resets it in a position to indicate a clean bag. It will be noted that the indicator member may be reset only in response to the manual operation of removing the dust bag.

Spring 48 may be made to have sufficient strength so that, when closure member 20 is detached from the casing 10, the spring will force rod 45 to the left, thus moving dust bag ring 17 out of contact with ring 15. This facilitates grasping the packing 19 on the ring without placing the hand within the ring. This is advantageous inasmuch as the interior of the ring is apt to be covered with dust.

10 The embodiment shown in Figs. 3 and 4 differ from that above described only in the nature of the indicator member. In this embodiment, the indicator member comprises a flat plate 55 rigidly secured to tubular member 30, and arranged 15 to move longitudinally with the member underneath an air tight window 56. Otherwise, the construction of the two embodiments is the same, and their operation is identical.

It will be noted that in the embodiments above 20 described the dust bag itself has been utilized as the distensible member movable by means of the pressure drop for imparting movement to the indicator.

In the following embodiments a separate dis- 25 tensible diaphragm is provided for this purpose and is arranged to be subjected on one side to the pressure existing within the dust bag and on the other side to the pressure existing within space 31 in the casing.

30 Referring to Fig. 5, reference character 10 again designates the casing of the vacuum cleaner unit provided with an end ring 15. Ring 15 has an enlarged portion 60 forming a recess opening from the space 31 within the casing. Mounted 35 within this recess is a cylindrical member 61 having a flat end 62 and an open end 63 of reduced diameter. End 63 is received within an opening formed in a member 64 secured to ring 15, and a bolt 65 is arranged to press against the end 62 40 to hold the member 61 in position. Ring 15 is formed with a passageway 66 communicating with the open end 63 and with an annular groove 67 formed in the face 16 of ring 15. Closure member 20 is formed with a similar groove 68 and the 45 flange 18 and packing 19 of dust bag ring 17 are formed with one or more openings 69 which establish communication between grooves 67 and 68. A passage 70 connects groove 68 with the space within closure member 20 and hence with 50 the interior of dust bag 27. A distensible member in the form of a flexible diaphragm 73 is secured within cylindrical member 61 by means of a ring 74 clamping the circumference of the diaphragm against a shoulder 75 of member 61. 55 Diaphragm 73 divides member 61 into a chamber 76 which is in communication with the interior of the dust bag through open end 63, passage 66, groove 67, opening 69, groove 68 and passage 70, and a chamber 77 which is in communication 60 with the space 31 through an opening 78 formed in the lower side of member 61. Reinforcing discs 79 and 80 are preferably secured to the central part of diaphragm 73 by means of a rivet 83. A spring 84 is disposed between disc 80 and the bottom 65 62 and is preferably secured in place around a cylindrical member 85 fastened to the bottom 62.

Slidably disposed within cylindrical member 61 is an indicator member 86 having a reduced end 70 87 adapted to be contacted by disc 80 of the diaphragm 73. Casing 60 is formed with an air tight window 87 in alignment with an opening 88 in the upper side of member 61 through which the position of indicator member 86 may be observed. A resetting rod 89 is slidably supported

within a stationary member 90 rigidly secured to member 61. The left hand end of rod 89, as viewed in Fig. 5, is provided with a head 93 adapted to press against the dust bag ring 17. Spring 94 is disposed between member 90 and head 93 5 and tends to move the rod 89 to the left. The right hand end of the rod is formed as a ring 95 slidable within cylindrical member 61.

The operation of this embodiment is as follows:

As described in connection with the previous 10 embodiments, the dust bag 27 offers a resistance to the flow of air therethrough which is proportional to the amount of dust accumulated therein, thus causing a lower pressure to exist within space 31 than within the dust bag. The higher pressure 15 within the dust bag is communicated to chamber 76 as previously described, and this pressure is exerted on the left hand face of diaphragm 73, while the lower pressure within space 31 is communicated to chamber 77 and acts upon the 20 right hand face of the diaphragm. Consequently, as the difference in these pressures increases, the central portion of diaphragm 73 is moved to the 25 right against the increasing resistance offered by spring 84. This movement causes indicator member 86 to move to the right. In the event of a subsequent decrease of the pressure drop, caused, for instance, by stopping the motor, spring 84 will move the diaphragm 73 back to its original position but indicator member 86 will remain in the 30 furthest position to which it has been moved, thus giving a reading which is proportional to the maximum pressure drop which has occurred through the bag since the machine was started.

When indicator member 86 indicates that the 35 bag should be cleaned, closure member 20 is unfastened and bag 27 removed. Spring 94 is now able to move rod 89 to the left and the ring 95 connected to the rod moves indicator member 86 back to its original position. As was the case in 40 the first embodiment described, if spring 94 is stiff enough, it will eject the dust bag ring a short distance when the closure member 20 is unfastened, thus making it easier for the operator to grasp the ring to remove the bag.

The embodiment shown in Fig. 6 differs from that illustrated in Fig. 5 only in that the head 93 of rod 89, contacts the dust bag ring 17 directly instead of having a portion of the dust bag material interposed therebetween. This may be accomplished by turning the material of the ring 17 50 back on itself as shown at 96 and securing the end of the bag 27 between the main part of the ring and the portion 96.

In the embodiment shown in Fig. 7, a cylindrical member 100 of glass or other transparent material is received within the space formed by the enlarged portion 60 of ring 15. One end of member 100 is received within a shallow cup-shaped member 101 provided with an opening 102 for establishing communication with the space 31 within casing 10. A flexible diaphragm 103 is clamped between the other end of member 100 and a shoulder 104 formed in a deep cup-shaped member 105. Secured within an opening formed 60 in the center of diaphragm 103 is a bushing 106 which is slidably mounted on a stem 107. Rigidly secured to bushing 106 is an indicator member 108 between which and the bottom of member 101 is disposed a spring 109.

70 Stem 107 is slidably mounted in an opening formed in ring 15 and a spring 110 is disposed between the right hand end of the stem and the bottom of member 101. Stem 107 is formed with a bore 113 extending axially from its left hand 75

end and communicating with a radial bore 114 which establishes communication with the space to the left of diaphragm 103. The left end of stem 107 is provided with a packing ring 115 which 5 seals the end of the stem against the inner face of closure member 20, the latter being formed with a passage 116 which establishes communication between bore 113 and the interior of the dust bag 27. Any suitable means may be provided for 10 positioning closure member 20 with respect to ring 15 so that passage 116 will be in alignment with the end of stem 107 when the closure member is secured in place. For instance, the closure member may be permanently hinged to the ring.

15 Rigidly secured to the central part of diaphragm 103 and indicator member 108 is a pin 117 having a portion of reduced diameter 118. Loosely mounted on stem 107 is disc 119 having a projecting edge 120. The reduced portion 20 118 of pin 117 extends loosely through the hole formed in disc 119 and a spring 123 is disposed between the diaphragm and disc 119. Due to the loose fit of stem 107 and pin 117 in the disc, the latter can be tilted a limited amount by spring 25 123.

The operation of this embodiment is as follows:

The pressure within dust bag 27 is communicated to the left hand side of diaphragm 103 30 through passage 116 and the bores 113 and 114 and stem 107, while the lower pressure existing within space 31 is communicated to the right hand space of the diaphragm through opening 102. The pressure difference acting on the dia- 35 phragm causes the central part thereof to move to the right against the force of spring 109 and indicator member 108 is caused to move in the same direction by virtue of the fact that it is rigidly secured to the center part of the dia- 40 phragm. During such movement bushing 106 slides on stem 107 and disc 119 likewise slides on the stem. Due to the tilted position in which the disc is held by spring 123, the disc does not bind 45 against stem 107 during movement in this direction. Upon a reduction in the difference in pressures acting on opposite sides of the diaphragm the spring 109 tends to move the central part of the diaphragm and the indicator member 108 attached thereto to the left. However, when pin 50 117 attempts to slide disc 119 along the stem 107, by applying force to the lower edge of the disc, the latter does bind and locks against the stem, thus preventing movement of the diaphragm to the left. Consequently, the indicator member 55 108 is retained in the furthest position to which it has been moved. When the closure member 20 is removed in order to take out the dust bag, spring 110 moves stem 107 to the left and dia- 60 phragm 103 and indicator 108 move along therewith, and thus return to their original position. When the projection edge 120 of disc 119 strikes the bottom of member 105, it is tilted to a more vertical position thus releasing the locking ac- 65 tion between the disc and stem 107. Spring 110 is not absolutely necessary, and if it is omitted spring 109 will move both the diaphragm and stem 107, which are locked together by disc 119, to the left when closure member 20 is removed. However, if spring 110 is omitted, stem 107 must 70 be extended so as to abut against the bottom of member 101 when the closure member is in place in order to maintain a tight seal at packing 115.

In the embodiments shown in Figs. 8 through 11, the indicating mechanism is located within 75 closure member 20, instead of within the casing

10. An advantage of this is that if the indicating mechanism gets out of order, it is not necessary to return the entire vacuum cleaner unit for repairs but a new closure member may be substituted and only the old closure member need be returned.

Referring to Fig. 8, closure member 20 is formed with an inwardly projecting cylindrical member 125 which is arranged to receive the hose 25. An annular flexible diaphragm 126 has its inner part secured in air tight relation to the inner end of member 125 while its outer circumference is secured to a member 127 supported by cylindrical member 125, the part of the diaphragm in between being movable. A member 129 is slidably supported on cylindrical member 125 and forced against diaphragm 126 by means of a spring 130. Closure member 20 is formed with an outwardly projecting portion 133 provided with an air tight window 134. A pin 135 is rigidly secured in portion 133 and an indicator member 136 is slidably mounted on the pin, and engages the pin with sufficient friction so that it is not movable accidentally. Indicator member 136 is provided with an extension 137 adapted to be contacted by member 129 when the latter is moved to the left as viewed in Fig. 8.

A cylindrical member 138 is slidably mounted within closure member 20 and a spring 139 tends to move member 138 to the right. However, when closure member 20 is secured to ring 15, member 138 presses against a packing ring 140 which prevents member 138 from moving with respect to the closure member. Member 138 is provided with a radially extending portion 143 which is 35 in axial alignment with a collar 144 on indicator 136. Ring 15 is formed with an opening 145 for establishing communication between space 31 within casing 10 and the space within closure member 20 to the left of diaphragm 126. This opening may be sufficiently small so that when the motor is started the reduction in the pressure acting on the left face of the diaphragm will not be so sudden as to cause the diaphragm to strike the indicator with such force as to 45 knock it further to the left than the diaphragm itself moves. Dust bag ring 17 is clamped between ring 15 and the outer circumference of diaphragm 126.

The operation of this embodiment is as follows:

The right hand face of diaphragm 126 is subjected to the pressure existing within dust bag 27 while the opposite face of the diaphragm is subjected to the lower pressure existing within space 31. This difference in pressure tends to move the diaphragm and member 129 to the left against the force of spring 130. Such movement causes indicator member 136 to be moved to the left, but movement of diaphragm 126 and member 129 in the opposite direction has no effect on the indicator. Consequently, the indicator records the maximum pressure drop which has occurred through the dust bag. When closure member 20 is removed in order to take out the 65 dust bag, spring 139 is able to move member 138 to the right, whereupon extension 143 strikes collar 144 of the indicator and moves the latter to the right, thus returning it to its original position.

In the embodiment shown in Figs. 9 through 11, a diaphragm 150 has its outer periphery secured within closure member 20, while its central movable portion is secured to a pin 151 which is slidably supported in a wall 152 within the 75

closure member. A spring 148 is disposed between the diaphragm and wall 152 and the diaphragm may be supported by a perforated plate 149 when the air pressures in opposite sides of the diaphragm are equalized. Ring 15 is formed with a passageway 153 communicating with a groove 154 formed in the face of the ring, while closure member 20 is formed with a similar groove 155, communication between these grooves being established by one or more openings 156 in the dust bag ring. A passage 157 connects groove 155 with the space to the left of diaphragm 150. Pivotally mounted on wall 152 is an indicator member 158. The friction caused by turning of the indicator about its pivot is sufficient to retain it in any position in which it may be set. An air tight window 159 makes the indicator 158 visible to the operator. An arm 160 connected to the indicator is arranged to be contacted and rotated in counterclockwise direction by movement of pin 151 to the left. Inasmuch as an increase in pressure drop through the dust bag causes diaphragm 150 to move to the left, indicator 158 records the maximum pressure drop which has occurred through the bag. The indicator is returned to its original position when the closure member 20 is removed by means of an arm 161 rigidly secured to a pin 162 which is slidably supported within the closure member, as will appear more clearly from Fig. 11. Pin 162 is provided with an enlarged head 163 and a spring 164 tends to move pin 162 to the right. Hence, when the closure member is removed the spring does move the pin to the right and arm 161 contacts arm 160 and rotates indicator 158 in a clockwise direction back to its original position.

In the embodiment shown in Fig. 12, a diaphragm 165 is mounted in closure member 20 so as to be subjected on one side to the pressure existing within the dust bag while the pressure of space 31 is communicated to the other side of the diaphragm through a passage 166 in ring 15 and a passage 167 in the closure member. A spring 168 tends to move the diaphragm to the right, while the pressure difference tends to move it in opposite direction. An indicator pin 169 is slidably mounted in an opening formed in closure member 20 and is arranged to be moved to the left by similar movement of the diaphragm. However, there is no connection between pin 169 and the diaphragm, and hence movement of the latter to the right will not move the pin. Inasmuch as the pin projects through the closure member to the atmosphere, a packing diaphragm 170 is provided for preventing leakage of atmospheric air. Inasmuch as the diaphragm 170 is subjected on one side to the low pressure existing within space 31 and on the other side to atmospheric pressure it will tend to resist movement of the pin 169 to the left. However, diaphragm 165 is made of sufficiently larger area so that the total force exerted by this diaphragm is larger than the force exerted by diaphragm 170. Friction producing means 171 are provided for retaining the indicator pin 169 in the furthest position to which it has been moved by the diaphragm 165. The distance that the outer end of indicator pin 169 projects is an indication of the maximum pressure drop which has occurred through the dust bag. In this embodiment the indicator member is not returned to its original position by removal of the closure member 20 but must be pushed in by the operator.

While there have been described several more or less specific embodiments to my invention, it is to be understood that these have been for purposes of illustration only and that the scope of the invention is not to be limited thereby, but is to be limited only by the appended claims viewed in the light of the prior art. 5

What I claim is:

1. In a vacuum cleaner, a dust separating member, means for producing varying flow of air through said member, a movable indicator member, means for moving said indicator member in one direction upon an increase in pressure drop through said dust separating member, said indicator member being arranged to remain in the position to which it is moved by the second mentioned means regardless of subsequent decrease in pressure drop, and means independent of said second mentioned means for moving said indicator member in the opposite direction. 20

2. In a vacuum cleaner, a dust separating member, means for producing varying flow of air through said member, a movable indicator member, means for moving said indicator member in one direction upon an increase in pressure drop through said dust separating member, said indicator member being arranged to be frictionally held in the furthest position to which it is moved by the second mentioned means, and manually operable means for moving said indicator member in the opposite direction. 30

3. In a vacuum cleaner, a removable dust separating element, means for producing flow of air through said element, an indicator member movable in one direction in response to an increase in pressure drop through said element, and means operable by removal of said dust separating element for moving said indicator in the opposite direction. 35

4. In a vacuum cleaner, a casing, a distensible member mounted in said casing, air flow means for producing a varying pressure differential on opposite sides of said member, means for limiting distension of said member to an amount proportioned to the pressure differential, an indicator movable in one direction to record the maximum distension of said member, and means responsive to a manual operation for moving said indicator in the opposite direction. 40

5. In a vacuum cleaner, a casing, a distensible dust separating member mounted in said casing, air flow means for producing a varying pressure differential on opposite sides of said member, resilient mechanism arranged to resist distension of said member and to be moved by distension thereof, an indicator movable in one direction to record the maximum movement of said mechanism caused by distension of said member, and means independent of said mechanism for moving said indicator in the opposite direction. 50

6. In a vacuum cleaner, a casing, a dust separating member removably mounted in said casing, air flow means for producing a pressure differential on opposite sides of said member, a movable member subjected on opposite sides to said pressure differential, means for limiting movement of said movable member to an amount proportioned to the pressure differential, an indicator movable in one direction to record the maximum movement of said movable member caused by the pressure differential, and means operable by removal of said dust separating member for moving said indicator in the opposite direction. 60

7. In a vacuum cleaner, a casing, a dust sepa- 75

rating member in said casing, air flow means for producing a varying pressure differential on opposite sides of said member, structure movable in one direction by an increase in pressure differential, resilient means for limiting said movement to an amount proportional to said increase, means for locking said structure against movement in the opposite direction upon a decrease in pressure differential, and means for releasing the locking means.

8. In a vacuum cleaner, a casing, a dust separating member removably mounted in said casing, air flow means for producing a pressure differential on opposite sides of said member, structure movable in one direction by an increase in pressure differential, resilient means for limiting said movement to an amount proportional to said increase, means for locking said structure against movement in the opposite direction upon a decrease in pressure differential, and means operable by removal of said dust separating member for releasing the locking means.

9. In a vacuum cleaner, a casing having an opening, a closure member for said opening, a dust separating member including a rim adapted to be clamped between said casing and said closure member, means for producing flow of air through said dust separating member, an indicator, means for moving said indicator in one direction upon an increase in pressure drop through said dust separating member to record the maximum pressure drop, and resilient means maintained under stress by said rim in clamped position for moving said indicator in the opposite direction and for moving said rim away from said casing when the stress is relieved by unclamping the rim.

10. In a vacuum cleaner, a casing having an opening, a closure member for said opening, a dust separating member including a rim adapted to be clamped between said casing and said closure member, and resilient means maintained under stress by said rim in clamped position for moving said rim away from said casing when said closure member is removed.

11. In a vacuum cleaner, a dust separating element, means for producing flow of air through said element, a member movable in one direction in response to an increase in pressure drop through said element, a spring for resisting said movement and for moving said member in the

opposite direction upon a decrease in pressure drop, an indicator for recording the maximum movement of said member in said one direction, and a manually releasable spring for resetting said indicator.

12. In a vacuum cleaner, a dust separating element, means for producing flow of air through said element, an indicator movable in one direction in response to an increase in pressure drop through said element, a spring for resisting said movement and for tending to move said indicator in the opposite direction upon a decrease in pressure drop, locking means for preventing movement in said opposite direction whereby said indicator records the maximum movement in said one direction, and manually operable means for releasing said locking means.

13. In a vacuum cleaner, a casing having an open end, a removable closure for said open end formed with an inlet port, a dust bag having a flanged rim, said rim being adapted to be disposed between said closure and said casing with the bag within the casing, means in said casing for producing flow of air through said bag, said bag offering resistance to the flow of air whereby a higher pressure exists in said bag than in the space within said casing and outside said bag, a pressure responsive member mounted in said casing with one side thereof communicating with said space, said casing, said rim and said closure being formed with communicating passages establishing communication between the opposite side of the pressure responsive member and the interior of said dust bag whereby said pressure responsive member is responsive to the pressure drop through said bag, and means for recording the response of said member corresponding to the highest pressure drop to which it is subjected.

14. In a vacuum cleaner, a distendible dust separating element, means for producing flow of air through said element, said element being arranged to be distended by the flow of air therethrough, means for yieldably resisting the distension of said element, a member for indicating and recording the maximum distension of said dust separating element, and means operable by removal of said element for resetting said member.

AXEL ALBERT FORSBERG. 50
